APPARATUS FOR DEVELOPING FILMS
WITHOUT A DARKROOMRaymond Huerta, Bronx, and Anthony Grendan-
in, New York, N. Y.

Application October 27, 1938, Serial No. 237,224

2 Claims. (Cl. 95—90.5)

This invention relates to apparatus for developing films without a darkroom.

An object of this invention is to provide apparatus of the character described, comprising a box or case having an opening with a black sleeve fastened over the opening, through which a hand may be inserted into the box for unreeling an exposed roll of film by means of apparatus within the box, so that the unreeled film may be placed within a developing tank within the box, while the box is closed.

A further object of this invention is to provide in apparatus of the character described, means for separately unreeling the film and paper of a roll of film within the box by means of a handle disposed on the outside of the box, means being further provided to start unreeling of the roll of film while the box is open.

A still further object of this invention is to provide portable apparatus of the character described, which shall be easy to manipulate, relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a perspective view of the apparatus embodying the invention;

Fig. 2 is a perspective view of the improved apparatus with the top of the case lifted open;

Fig. 3 is an elevational, cross-sectional view through the handle and paper receiving reel;

Fig. 4 is a longitudinal, vertical, cross-sectional view through a portion of the apparatus;

Fig. 5 is a top plan view of a portion of the apparatus and

Fig. 6 is a view similar to Fig. 4, but illustrating a modified construction.

Referring now in detail to the drawings, 10 designates apparatus embodying the invention, comprising a box or case 11, having a base portion 12, and a top or cover portion 13. The base portion 12 has a bottom wall 15, short upstanding front and rear walls 16, and short upstanding side walls 17.

The cover 13 comprises a top wall 19, a front wall 20, a rear wall 21, and side walls 22. The

lower edge of one of the side walls 22 is hinged, as at 24, to the upper end of one of the side walls 17 of the base. When the cover is closed, the bottom edges of the cover rest on the upper edges of the base. The cover is considerably taller than the base, so that when the cover is open, the film unwinding apparatus 25, mounted on the base, projects upwardly from the base. A supporting chain 26 may interconnect the base with the cover. The front wall 20 of the cover 10 is formed with an opening 27. The opening may be closed by a door 28.

Fastened to the edges of the opening is a cloth sleeve 29, having an elastic inner edge 30. The sleeve projects into the case. When the door 28 is opened, a hand may be inserted into the box through the sleeve, and the elastic edge grips the wrist, so that no light can enter the case. Any suitable fastener means 32 may be provided to retain the cover in closed position on the base.

On the bottom wall 15 of the base 12 is a base plate 35, on which unwinding apparatus 25 is mounted. Said apparatus comprises a pair of spaced, vertical, upstanding supports 36. Attached to one of the supports 36 is a horizontal, cylindrical member 37 having an end wall 38 formed with a central opening 39. Said support 36 is formed with an opening 40, co-axial with the opening 39.

Extending through the openings 39, 40 is a reel unwinder member 42. The member 42 has a key 44 at one end adapted to be received in the usual key slot at one end of a film spool 45. Extending from the key 44 is a stem 46, passing through the opening 39. A coil compression spring 47 is interposed between the key and the end wall 38 of the cylinder. On stem 46 is a circular head 48 formed with a pair of diametrically opposed openings 49, for the purpose hereinafter appearing.

The other support 36 has a fixed pintle to receive the other end of the spool 45. The head 48 is furthermore formed with a radial screw threaded opening 50. A small angular handle member 51, having a screw threaded end portion, 45 may be screwed into the opening 50, to start unwinding of the spool 45, when the cover is open, as shown in Fig. 2 of the drawings. The spool 45 may be released from the supports 36 by pulling the member 42 to the right, against the pressure of the spring 47, to withdraw the key 44 from the key slot in the spool.

Means is further provided to wind the spool 45 when the cover is closed. To this end, one side wall 22 of the cover is formed with a through

40

35

45

50

55

opening 55, aligned with spool 45. Attached to the inner and outer sides of said wall 22 are rings 56 and 57, having openings registering with the openings 55.

5 Extending through the opening 55 and the openings in the rings 56, 57, is a rod 60. Attached to the outer end of the rod 60, and disposed on the outside of the box, is a handle 61. Attached to the inside of the rod 60 is a head 10 62, having a pair of spaced pins 63, adapted to be received within the openings 49 of head 48. Interposed between the head 62 and the ring 57 is a coil compression spring 64.

When the cover is closed the spring 64 pushes 15 the pins 63 into the openings 49, so that when the crank handle 61 is turned from the outside of the box, spool 45 will be rotated.

There is further mounted on the base plate 20 35, a pair of parallel upstanding supports 66, aligned with the supports 36. On the upper end of one of the supports 66 is a fixed pintle 67, to support one end of a horizontal film spool 68. At the upper end of the other support 66 is a spring pressed pintle 69 adapted to releasably support the other end of the spool 68.

On the base plate 35 is another pair of vertical upstanding supports 70, parallel and aligned with the supports 66. At the upper end of the supports 70 is rotatably mounted a horizontal 30 idler shaft 71.

There is further mounted on the base plate 35, an upstanding support 73, provided with a short horizontal shaft 74, parallel to spools 45 and 68 and shaft 71. Mounted on the shaft 74 35 is a spiral film holder 75. The film holder 75 has a pair of parallel, similar, symmetrically disposed, spaced walls 77, formed on the inner surfaces thereof, with spiral grooves 78. Walls 77 are interconnected by an axial hollow shaft 40 frictionally receiving the shaft 74. The member 75 may be slipped off the shaft 74.

There may also be placed within the case 11, a suitable tank adapted to contain film developing solution, and to receive the film holder 75. Said tank may be of any suitable well known construction and is therefore not illustrated in the drawings.

The method of using the improved apparatus will now be described:

50 The cover is first opened, and holder 75 placed on shaft 74. A roll 79 of exposed film is then mounted on the pintles 67, 69 at upper ends of the supports 66. The sheet of paper 80 from the roll 79 is wound over the idler shaft 71 and the end thereof inserted into the usual slot in the spool 45 on the supports 36. The film 82 from the roll 79 is inserted into the grooves 78 of the film holder 75. The unwinding of the paper is begun by using the handle 51 screwed 60 to the opening 50.

It will be noted that as the paper is unwound, the film will push its way into the grooves 78. After the paper is somewhat unwound, the handle 51 is removed and the cover 13 is closed. 65 Before the cover is closed, the handle 61 is drawn back to retract the head 62, pressing the spring 64. When the cover is down on the base 12, the handle is released and somewhat turned so that the pins 63 will snap into the openings 49.

70 The handle 61 may then be turned until the film 82 is completely unwound from the roll 79 and pushed completely into the spiral tracts or grooves 78, so that the film is completely mounted on the holder 75. The door 28 may then be

opened and a hand inserted through the sleeve 29 into the box. The holder 75 may then be slipped off the shaft 74 and inserted into the film developing tank (which is in the box), for development.

5 In Fig. 6 there is shown a modified construction. In said figure, the base 35 is provided with a support 73 to removably support the film holder 75. On the base 35 are a pair of upstanding supports 66, disposed on one side of 10 the film holder for supporting a roll of film 79 to be unwound.

On said base 35 are a pair of supports 36, disposed on the other side of the film holder 75, and supporting a spool 45 and unwinding mechanism, similar to that shown in Fig. 3, of the drawings. With this arrangement, the idler 71 is eliminated as the film 82 is unwound from the roll 79 to the film holder 75, and the sheet of paper 80 is unwound directly onto the spool 45. 20

It will thus be seen that there is provided a device in which the several objects of this invention are achieved, and which is well adapted to meet the conditions of practical use.

As various possible embodiments might be made 25 of the above invention, and as various changes might be made in the embodiments above set forth, it is to be understood that all matter herein set forth or shown in the accompanying drawings is to be interpreted as illustrative and 30 not in a limiting sense.

Having thus described our invention, we claim as new and desire to secure by Letters Patent:

1. Apparatus of the character described comprising a case having a base, and a cover for 35 said base hinged thereto and having side, front and rear walls, one of the walls of the cover being formed with an opening, and a flexible sleeve attached to said cover and surrounding the opening and extending into the case, means 40 on said base to rotatably support a roll of film, a spool on said base receiving the paper from said roll, a spiral film holder adapted to receive the film from said roll, means on the base to removably support said spiral film holder, means 45 on the cover to concurrently unwind the paper and film from said roll of film onto said paper spool and film holder, respectively, a door for closing the opening in the cover, and means for unwinding the film and paper from said roll, 50 with the cover opened up.

2. Apparatus of the character described, comprising a case having a base, and a cover for said base hinged thereto and having side, front and rear walls, one of the walls of the cover 55 being formed with an opening, and a flexible sleeve attached to said cover and surrounding the opening and extending into the case, means on said base to rotatably support a roll of film, a spool on the base for receiving the paper from 60 said roll, a spiral film holder adapted to receive the film from said roll, means on the base to removably support said spiral film holder, means on the cover to concurrently unwind the paper and film from said roll of film onto said paper 65 spool and film holder, respectively, a door for closing the opening in the cover, means for unwinding the film and paper from said roll, with the cover opened up, and an idler shaft adapted 70 to engage the sheet from said roll, between the roll and the paper receiving spool.
